TION OF OHIO.

DISPLAY DEVICE.

1,308,949.

Specification of Letters Patent.

Patented July 8, 1919.

Application filed February 25, 1916. Serial No. 80,409.

To all whom it may concern:

Be it known that we, JAMES HARRIS and ROBERT D. BOGUE, citizens of the United States, and residents of Wyoming, in the county of Hamilton and State of Ohio, and Cincinnati, in the county of Hamilton and State of Ohio, respectively, have invented certain new and useful Improvements in Display Devices, of which the following is a specification.

Our invention relates to means for displaying articles of merchandise, or advertising, or other matter; and its object is to facilitate the preparation of the merchandise or other matter for display when it is received packed or wrapped, or otherwise in inclosed condition.

Our invention consists in the combination of parts and in the details of construction and arrangement of parts as will herein be more fully described and claimed.

In the drawing:

Figure 1 is a perspective view of a container with merchandise therein, and provided with our invention as we prefer to construct it;

Fig. 2 is a front elevation of the same on a plane parallel to the front of the container;

Fig. 3 is a similar rear elevation of the same;

Fig. 4 is a bottom plan view of the same with the parts in the positions that they occupy when the container is inclosed in its cover, but with the cover omitted for sake of clearness;

Fig. 5 is a perspective view of the same with the cover thereon, but partially withdrawn therefrom, showing how the parts assume their operative positions as the cover is withdrawn;

Fig. 6 is an enlarged longitudinal section through part of the bottom of the container and through the operative parts on a plane corresponding to the line 6—6 of Fig. 2;

Fig. 7 is a view similar to Fig. 4, but showing a modification of our invention; and

Fig. 8 is a partial section similar to Fig. 6, but on a plane corresponding to the line 8—8 of Fig. 7, and showing the operative relation of the operative parts in the modification.

The preferred use of our invention is in facilitating the display of small packages of merchandise, especially confections, such as candy, chewing gum and the like. Accord-

ingly, the illustrations have been confined to such use, and the drawing shows a rectangular box or container 1 with a flat bottom 2, made in any approved manner out of any suitable material, such as paste-board or card-board. This box 1 contains the articles of merchandise 3, and preferably at its rear end it has an upright card or sign 4 which may be of any suitable material, such as paste-board or card-board, and may be secured in or to the box 1 in any suitable manner. Such a sign, may, as indicated, bear an advertisement of the merchandise contained in the box 1 or marks denoting the price thereof, or may display other advertising matter or any other matter desired, as is well known in the use of display cards or signs. This card or sign 4 may lie in the box over the top of the merchandise 3 when the package is closed for storage, shipping and handling.

Fitting around the box 1, closing its top and covering the merchandise 3 and the card or sign 4, if contained therein, is a slide cover 5, shown fully only in Fig. 5, but indicated by dotted lines in Figs. 2 and 3. This slide cover 5 may be of material similar to that of the box, and fitting the box snugly, as is well known in the construction and arrangement of containers of this kind.

It will be understood that the box 1 and the slide cover 5, as above described, are old and well-known structures; and they are described in detail only to more fully elucidate the description of the novel elements of our invention which are incorporated with said box and cover, and which coöperate therewith in a novel manner.

Thus, a single sheet 6 of suitable material, such as paste-board or card-board of sufficient thickness, is provided, preferably closely approximating in length and width the length and width of the flat bottom 2 of the box or container 1; and an end part 7 of this sheet 6 is bent down upon the other part, which other part 6 has its flat side secured against the flat bottom 2 of the box or container 1, as clearly seen in Fig. 1. Thus the part 6 forms the support for the box or container 1, while the part 7, when bent down, forms a prop to keep the supporting part 6 at such an inclination that the box or container 1 will be supported in an inclined position as seen in Fig. 1, and which position, in itself, is not novel, it being 110

common to support boxes of merchandise in such a position in order to more prominently display their contents.

However, where containers have been thus supported, it has been necessary to exercise some care in selecting a suitable prop or supporting means to maintain the inclined position; or, where the box has been supplied with some kind of prop or easel, this 10 has required considerable attention in order to bring it into its operative condition when the container is opened or unpacked. It is found in actual commercial experience that where a container requires much attention, it is very likely to not be brought into such an advantageous position by the merchant receiving it; with the result that the merchandise contained in such a container is not as well displayed nor as rapidly sold as it might be. It is found that a merchant receiving a container of merchandise with any kind of device that necessitates his learning how to set it up, is not very apt to set up the container as it 25 should be.

In view of these circumstances, we not only provide the sheet of material 6 with its bent-down part 7; but provide means for at once automatically bringing said 30 part or prop 7 into the proper position to render the most stable support for the supporting means and the supported box or container 1 and thenceforth to hold it in such position.

35 Thus, a transverse slot 9 is cut in the sheet of material 6, preferably with one side lying approximately on the line of folding 8, and with its ends a considerable distance from the adjacent sides of the sheet 40 and having longitudinal slots 10 extending from these ends along the sheet 6 in direction away from the line of folding 8, and continuing as slits 11. Thus, a brace 12 is left which may, on a transverse line 13 45 which connects the ends of the slits 11, be bent down in the same direction that the prop 7 is on the line 8. It will be seen that the slot 9 and the slots 10 extending to the slits 11 are merely continuations of 50 the slits 11, so far as concerns merely allowing this separation of the brace 12 from the main part of the material.

The brace 12 thus formed, has, at opposite sides, notches 14 extending inward 55 toward each other, but inclined toward the free end of the tongue; thus leaving a hook-shaped part 15 at each side near the free end of the brace. The prop 7 has, cut in its free end part, notches 16 which 60 incline in toward each other, leaving in the middle of the free end of the prop 7 a lug 17. An elastic band 18, such as an ordinary rubber band, has the opposite lateral strands passed under the hooks 15 and 65 through the notches 14 of the brace 12, and

has its end loop brought past the free end of the brace; whereupon the other end loop of the band is brought through this loop, thus securing the band to the brace 12. This other end loop of the band 18, when 70 thus brought through, is brought over the lug 17 and into the notches 16 of the prop 7, thus connecting it to the free or lower end of the prop 7. This formation of the parts and arrangement of the band 18 is 75 best seen in Fig. 4, which shows the device in its flattened condition that it has when the prop 7 and brace 12 are not bent down. This is the condition that the device has when it is placed against the bottom 2 of 80 the box or container 1 in such relative position that the prop 7 and brace 12 are bent down from the bottom 2 and the slide cover 6 is slid onto the box with its bottom 19 coming under the various parts of the device and holding them up against the bottom of the box, maintaining the device in its flattened condition.

It will be seen that if the elastic band 18 normally has less length than is required 90 to pass around the hooks and lug, as above described, with the parts in flattened condition, the band 18 will be stretched; and, by tending to resume its normal length, will pull the free end of the prop 7 down under 95 the brace 12, and will pull the brace 12 down against the adjacent side of the prop 7, thus acting as a gage to insure the correct positioning of the prop 7, as well as thereafter acting as a brace for the prop 100 against further swinging of the prop toward the main part of the sheet of material 6. The prop and brace are so proportioned that the weight imposed upon the main part 6, with the prop 7 supporting it as 105 hereinbefore described, will tend to swing the prop toward the brace. Thus the elastic band 18, after having effected the automatic positioning of the parts, is relieved of further duty except to hold the free end 110 of the brace 12 well up on the prop 7, guarding against slippage of the lower or free end of the prop 7 up over the end of the brace, which might occur in some cases, with results injurious to the structure. 115

From the foregoing, it will be seen that the prop 7 and brace 12 will, under the action of the elastic band 18, assume their proper positions as soon as the bottom part 19 of the slide cover 5 is withdrawn from 120 them in either direction. Fig. 5 makes this clear, where the slide cover is indicated as being withdrawn forwardly from the box or container 1 and the operative parts on the bottom thereof. Thus it will be seen that 125 there is absolutely no need of any attention in order to bring the operative parts into their operative positions. In fact, it is difficult to prevent them from assuming their correct positions when the slide cover 130

5 is withdrawn from the box or container 1; and even though a merchant is not aware that the box or container is provided with any means for supporting it in any special 5 position, the means will be brought into operative condition nevertheless; after which its method of operation is so obvious that even the most inattentive person must become aware thereof. Then, not having 10 any positive objection to displaying the merchandise in this way, but only having had a negative objection on account of the attention required in setting up a device that does not adjust itself automatically, the merchant 15 will leave the box or container supported in the desired manner.

It will be seen that the slot 9 is provided rather than merely a slit, because it leaves room for the strands of the elastic band 18 20 when the parts are in flattened condition. The other slots 10 are provided rather than merely slits, for convenience in manufacture, since this enables the slot 9 and the notches 14 in the sides of the tongue 12 to all be cut 25 with the same punch and die. It will also be seen that it is advantageous to have the line of folding 8 coincident with the longest side of the slot 9 and the line of folding 13 coincident with the ends of the slits 11; be- 30 cause the material folds more readily at these points, and it is thus possible to afford more uniform folding if this operation is performed by hand. Likewise, it is preferable, as hereinbefore alluded to, to have the 35 sheet of material 6 as near as practicable the same size as the bottom 2 of the box or container 1, thereby affording the maximum surface for attachment to the box or container 1, which is preferably by pasting or 40 gluing.

It will be understood, however, that these minor details may be varied as desired, or in accordance with particular requirements, such as when different kinds of material are 45 used in making the parts, or where the box or container must have some different shape than that herein shown. Likewise, it will be understood that the use of the parts thus combined and arranged for automatic as- 50 sumption of operative position is not confined to the support of a container; but that they may be made to support a mere card or sign or any other object which it is desired shall be supported in any required po- 55 sition for any reason. In this connection it may also be noted that the angle of inclination may vary considerably from that herein indicated; this being readily accomplished, by varying the relative proportions of the 60 parts with due regard to the stability of the object when supported.

In Figs. 7 and 8 is shown another example of our invention in which the parts when they have been brought into their opera- 65 tive positions, may be secured therein with

more permanence than is afforded merely by the holding of the elastic band in the preceding example. The modified prop 7' and brace 12' have, as in the preceding example, the notches 14 and 16 defining the hooks 15 70 and lugs 17, and the elastic band 18 will make this modified device automatically come into operative condition, whereupon the permanent fastening means may be made to supplement the band 18 in holding the 75 parts in their proper position; or, where automatic positioning of the parts is not required, the elastic band may be dispensed with.

As here shown, this more permanent fas- 80 tening means comprises a tongue 20, preferably a small strip of thin metal, which has at one end a hook 21 passing through a small slot 22 in the end part of the brace 12' and clenched against the upper side of the brace, 85 and a free end part 23 that projects past the end of the brace 12' to pass through a small slot 24 in the free end part of the prop 7' and be bent down on the side thereof away from the engaging end of the brace 90 12', as clearly shown in Fig. 8.

Having fully described our invention, what we claim as new and desire to secure by Letters Patent is:

1. In a display device, in combination 95 with means to hold matter to be displayed, a prop and a brace hinged to said means to swing downward against each other, whereby the brace holds the prop in operative position to support said means in position 100 for display of said matter, said prop and brace being adapted to lie against the side of said means, out of operative position, removable means for holding said prop and brace against said side, and self-acting 105 means connected to said prop and to said brace, respectively, to automatically swing said prop and brace down from said side and hold the end of the brace against the lower end part of the prop. 110

2. In a display device, in combination 115 with means to hold matter to be displayed, a prop and a brace hinged to said means to swing downward against each other, whereby the brace holds the prop in operative position to support said means in position for display of said matter, self-acting means connected to said prop and to said brace, respectively, to automatically swing them together, and means supplementary to said 120 self-acting means to hold said prop and brace together in inoperative position.

3. In a display device, in combination 125 with means to hold matter to be displayed, a prop and a brace hinged to said means to swing downward against each other, whereby the brace holds the prop in operative position to support said means in position for display of said matter, self-acting means connected to said prop and to said brace, 130

- respectively, to automatically swing them together, and means on said brace extending through said prop to hold said brace and prop together in operative position.
- 5 4. In a display device, in combination with means to hold matter to be displayed, a prop and a brace hinged to said means to swing downward against each other, whereby the brace holds the prop in operative 10 position to support said means in position for display of said matter, said prop and brace being adapted to lie against the side of the said means, out of operative position, and self-acting means connected to said 15 prop and to said brace, respectively, to automatically swing said prop and brace down from said side and hold the end of the brace against the lower end part of the prop, and a removable cover slid onto and surrounding said article, with its bottom sliding across said prop and brace and holding them up against said side.
- 5 5. In a display device, in combination with an article having a flat side, a single 20 flat sheet of material comprising a flat main part with its flat side attached to said flat side of said article and having a recess in it, and comprising a flat prop hinged to one end of said main part and adapted to lie up against said flat side of the article, and comprising a brace hinged on said main part in said recess therein to lie up against said flat side in substantially the same plane as that of the prop when lying against said 25 flat side, said prop and brace being adapted to swing down against each other whereby the brace holds the prop in operative position to support said article in position for display.
- 40 6. In a display device, in combination with an article having a flat side, a single flat sheet of material comprising a flat main part with its flat side attached to said flat side of said article and comprising a flat prop hinged 45 to one end of said main part and comprising a brace hinged on said main part, said prop and brace being adapted to swing down against each other whereby the brace holds the prop in operative position to support said 50 article in position for display, said prop and brace being adapted to lie against said flat side of the article, out of operative position, removable means for holding said prop and brace against said side, and self-acting 55 means connected to said prop and to said brace, respectively, to automatically swing said prop and brace down from said side and hold the end of the brace against the lower end part of the prop.
- 60 7. In a display device, in combination with an article having a flat side, a single flat sheet of material comprising a flat main part with its flat side attached to said flat side of said article, a flat prop hinged to one 65 end of said main part and adapted to lie up against said flat side of the article, a brace hinged on said main part to lie up against said flat side, said prop and brace being adapted to swing down against each other whereby the brace holds the prop in operative position to support said article in position for display.
8. In a display device, in combination with an article having a flat side, a single flat sheet of material comprising a flat main part with its flat side attached to said flat side of said article and comprising a flat prop hinged to one end of said main part and comprising a brace hinged on said main part, said prop and brace being adapted to swing down against each other whereby the brace holds the prop in operative position to support said article in position for display, said prop and brace being adapted to lie against said flat side of the article, out of operative position, contractible means connected to said prop and to said brace, respectively, to automatically swing said prop and brace down from said side and hold the end of the brace against the lower end part of the prop, and a removable covering surrounding said article, with its bottom across said prop and brace and holding them up against said side.
9. In a display device, in combination with an article having a flat side, a single flat sheet of material comprising a flat main part with its flat side attached to said flat side of said article, one end of said main part being bent down to form a flat prop adapted to lie up against said flat side of the article, said main part having a transverse cut near the line of bending of said prop, and having other cuts or slots extending longitudinally from near the end of said cut or slot in direction away from said line of bending, and the part of the material between said cuts being bent down, thereby forming a brace hinged on said main part to lie up against said flat side, said prop and brace being adapted to swing down against each other, whereby the brace holds the prop in position to support said article in position for display.
10. In a display device, in combination with an article having a flat side, a single flat sheet of material comprising a flat main part with its flat side attached to said flat side of said article, one end of said main part being bent down to form a flat prop adapted to lie up against said flat side of the article, and having notches in its free end, forming a lug between the notches, said main part having a transverse cut near the line of bending of said prop, and hav-

ing other cuts extending longitudinally from near the ends of said cut or slot in direction away from said line of bending, and the part of the material between said 5 cuts being bent down, thereby forming a brace hinged on said main part to lie up against said flat side or to incline toward the prop when swung down, said brace having in opposite sides notches extending in 10 ward toward each other, and self-acting means connected to said prop and to said brace, respectively, near their free ends by passing around said lug and through the notches in the brace, and adapted to automatically swing said prop and brace down 15 from said part and hold the end of the brace against the lower end part of the prop.

11. In a display device, in combination with a rectangular container having a flat 20 bottom, a single flat sheet of material comprising a flat main part with its flat side attached to said bottom, a flat prop hinged

on one end of the main part and adapted to lie up against said bottom, a brace hinged on said main part to lie up against said bottom, said prop and brace being adapted to swing down against each other whereby the brace holds the prop in position to support said container in position for display, self-acting means connected to said prop 25 and to said brace, respectively, to automatically swing said prop and brace down from said bottom and hold the end of the brace against the lower end part of the prop, and a rectangular slide cover surrounding said 30 container, with its bottom sliding across said prop and brace and holding them up against said flat bottom.
